UNITED STATES PATENT OFFICE

WILLIAM F. MCKAY, OF LA GRANGE, ILLINOIS

DEVICE FOR SUPPORTING BEDCLOTHES

Application filed March 31, 1928. Serial No. 266,270.

My invention relates to beds and more particularly to a support for elevating the covers at the foot of the bed so that they will not press against the feet of the occupant of the 5 bed.

The principal object of my invention is to provide a cheap, simply constructed and operated and also readily installed device which may either lie flat beneath the bed 10 clothes or be elevated to raise the latter and so take their weight off the feet.

A further object is to produce a device of the above character suitable to insert and remain in position ready for use at foot, head 15 or side in a made-up bed and adapted to concealment from observation by conforming adjustably to the top surface of the mattress and by embedment in the mattress and bed clothes thereof.

20 Another object is to produce a device of the above character formed to substantially conform to and substantially confine to the outline of a sectional view of the edge portion of a mattress.

25 A still further object is to produce a device of the above character adapted to elevate and support the clothes to a practical height substantially straight up from the outside edge of the mattress in one position and in another position to support the clothes in an inclined position from the edge of the mattress, means being provided for compensation for loss in height of the supporting device in the second position due to its inclination.

30 Other and further important objects of the invention will be apparent from the disclosures in the following description which sets forth the preferred form of my invention.

40 In the drawings:

Figure 1 is a rear elevation of the device in extended position.

45 Figure 2 is a side elevation of the same with a part in section.

Figure 3 is a section on the line III—III of Figure 2.

Figure 4 is a section on the line IV—IV of Figure 1.

50 Figures 5 and 6 are views similar to Figure

4 showing the parts in different relative positions.

Figure 7 is a rear elevation of a part of the end of a bed with the device in position thereon.

55 Figure 8 is a side elevation of the same.

Figure 9 is a view similar to Figure 8 but showing the bed clothes support in three different positions.

60 Figure 10 is a detail view partly in section of a modified form of construction.

Figure 11 is a section on the line XI—XI of Figure 10.

65 As shown on the drawings:

The device comprises a base A formed of a single length of stout rod having a central horizontal U-shaped part or bight 1. The ends of this U-shaped portion or bight are first bent outwardly at 2, then upwardly at 3, then forwardly at 4 and inwardly at 5 thus forming stops or abutments. Each of these bends in the rod has its own particular purpose, as will be described later.

70 The bed clothes support B proper is likewise formed of a single length of stout rod having a central U-shaped part 6. The ends of this U-shaped portion are bent forwardly and then around the parts 3 of the base A to form loops 7.

75 The U-shaped part 6 of the clothes support B is shorter than the distance between the uprights 3 of the base A so that it may swing therebetween except as otherwise restricted. This swinging movement is restricted in one or other or both of two ways. 80 First, the inwardly projecting tips 5 of the base A may engage the arms of the clothes support B as shown in Figures 1, 2 and 4. Second, the loops 7 may bind the parts 3 as a result of the tilting of the clothes supporting 85 member B and so prevent further tilting of the latter. As shown, the loops are bent at an acute angle with respect to the arms of the support to cause the binding action to occur earlier in backward movement and later in 90 forward movement than would otherwise be the case, as indicated in Figure 2. As shown in Figures 1, 2 and 4, the parts are in such a position that both of these methods are involved. When the supporting member B is 95 100

raised, contact with the tips 5 ceases and the supporting member is held at the angle shown in Figures 1, 2 and 4 solely by the binding of the loops 7 on the uprights 3. When the supporting member is lowered, the binding of the loops 7 ceases but the tips 5 compel the supporting member to assume a position which becomes progressively more vertical as the loops 7 slide down the uprights 3.

10 The upper ends of the uprights 3 are bent forwardly at 4 and then inwardly at 5. The purpose and function of this forward bend 4 is to allow the clothes supporting member B to swing forwardly until such member lies horizontally on the bed as shown in Figure 15 6, without the loops 7 binding.

10 The support B should preferably be free to swing not merely into horizontal position but below for various reasons. First, the thickness of the mattress and clothes thereon 20 may vary, and it is desirable to allow the support to rest on the mattress when the surface of the latter is in the same horizontal plane as the loops 7 or slightly below the same. Second, the support should be free to swing downwardly until the central part 6 of the support rests on the central part of the base. These contacting portions may then be tied together so as to form a compact parcel for shipment.

30 The lower ends of the uprights 3 are bent inwardly at 2 to prevent the loops 7 passing from the uprights 3 onto the arms of the horizontal U-shaped part 1 of the base. In its lowermost position the clothes supporting member B assumes the position shown in dotted lines in Figure 2, except, of course, when drawn forward to contact with the tips 5 by the pressure of the bed clothes thereon.

40 In Figures 10 and 11 a modification is illustrated consisting of a yoke 8, the arms of which are apertured for the passage of the uprights 3. The arms are arranged on either side of the loops 7 so that by locking the yokes 8 to the uprights 3, the loops 7 are likewise locked against sliding movement on the uprights. The locking means consists of a thumb screw 9 passing thru the center of the yoke and bearing against the loop 7. As shown, the uprights 3 may to advantage be flattened and the loops 7 correspondingly flattened so as to give a greater grip between such parts.

50 In operation, the horizontal part 1 of the base A is slipped under the mattress at the end of the bed, as shown in Figures 7, 8 and 9. The width of the device is preferably such that its sides do not come to the side edges of the mattress but are positioned a distance therefrom, as shown in Figure 7. The uprights 3 are preferably of such height that when the clothes supporting member B is in its horizontal position, neither the latter nor the upper ends of the uprights will project materially above the top of the mattress and

preferably be embedded in the vertical and top surfaces of the mattress.

60 The bed is usually made up with the clothes supporting member horizontal. Then the occupant of the bed can elevate the member by 70 merely raising it with his toes and pushing it backwards when the pressure of the clothes on the member will cause the latter to slide down the uprights until either the loops 7 or the tips 5 hold the member in more or less upright position.

75 The clothes support is arranged so that it has three positions of adjustment, one substantially vertical, another substantially horizontal forwardly, and the third at an angle intermediate the first two positions. The first and last positions are used according as occasion demands that the clothes be elevated to their maximum height close to the foot, edge or head of the mattress or at a distance therefrom. For instance, when a sick person is lying propped up by pillows for eating, reading or the like, the feet are drawn up away from the bottom of the mattress into the position shown in dotted lines in Figure 9. 80 When, however, the sick person wishes to sleep, the body is moved toward the foot of the bed so that the feet are then close to the foot of the mattress. The first position of the feet requires the inclined position of the 85 clothes support and the second position of the feet requires the vertical position of the clothes support.

90 As the clothes support is moved from the substantially vertical to the inclined position, the upper margin tends to drop. In the construction shown, this tendency is counterbalanced by the fact that the loops of the support about which the latter swings are lower in the vertical than in the inclined position, 100 so that the actual height of the upper margin or central part of the clothes support above the mattress is substantially the same in both vertical and inclined positions.

105 The construction of the device from rod or heavy wire is not only very cheap and simple to manufacture, but also has the great advantage that the device, on account of the narrowness of the parts, will readily embed itself in the mattress and clothes as indicated 110 in Figures 7, 8 and 9.

115 In other words, the ratio of the weight of the bed coverings on the support to the resistance of the mattress and clothes to embedding of the support into the latter is much greater than it would be were the support formed of sheet metal or the like having a large superficial area of contact with the bed.

120 For hospital use it may be desirable to 125 make the distance between the uprights greater than the width of the mattress to allow the latter to be slipped therebetween. With such construction, the arms of both base and clothes supporting member would preferably 130

be inclined toward their outer portions, the inclination of the arms of the base being to secure proper support and the inclination of the arms of the clothes supporting member being to avoid undue elevation of the clothes at the sides of the bed.

I am aware that many changes may be made, and numerous details of construction may be varied through a wide range without departing from the principles of this invention, and I therefore do not purpose limiting the patent granted hereon, otherwise than necessitated by the prior art.

I claim as my invention:

15 1. A device of the class described comprising a base member, said base member consisting of a single length of wire in U-shaped formation with the end portions bent upwardly providing a pair of uprights, a clothes supporting member having loops thereon encircling said uprights and slideable and swingable thereon, said uprights having stops thereon in the path of movement of said supporting member for limiting forward angular movement of the supporting member with respect to the base member.

20 2. A device of the class described comprising a member having a pair of uprights connected together at the lower ends thereof, and bent at an angle to said members to form a bight as a base for said members, a clothes supporting member having arms terminating in loops encircling said uprights and slideable vertically thereon, and forwardly and laterally bent tips on said uprights in the path of movement of said supporting member engageable by said arms to limit forward movement of said supporting member with respect to said base member.

25 3. A device of the class described comprising a base member consisting of a single length of rod in U-shaped form and having upright arms, a clothes support member consisting of a single length of rod in U-shaped form, the arms of which have loops at the end encircling the upright arms of the base member, the distance between the insides of the arms of one of said members being greater than the distance between the outsides of the arms of the other member to allow one member to swing forwardly inside of the other member to allow one member to swing forwardly inside of the other member, and forwardly and laterally bent tips on the upright arms of the base member to limit the extent of such swinging movement.

40 4. A device of the class described including a base member, said base member consisting of a single length of wire in U-shaped formation, the end portions being bent upwardly at right angles to the plane of the base, a clothes supporting member having loops encircling said upward bent portions movably connected thereto and capable of

sliding and swinging movement thereon, and stops on one member for limiting forward swinging movement of the other member in one direction.

45 5. A device of the class described comprising a base member, a clothes supporting member having loops thereon engaging said base member and slideable and swingable thereon, said base member having abutments thereon in the path of movement of said supporting member for limiting angular movement of the same in one direction and out of the path of movement of said supporting member when swung in the opposite direction to allow the free margin of the supporting member when swung in the said opposite direction to fall below the point of pivotal connection between the two members.

50 6. A device of the class described including a base member, said base member consisting of a single length of wire in U-shaped formation, the end portions being bent upwardly at right angles to the plane of the base, a U-shaped clothes supporting member having loops on the ends of the arms engaging the uprights of the base members for sliding and swinging movement of the supporting member on the base member, and stops on one of said members positioned to limit the forward movement of the supporting member relatively to the base member in one direction when the ends of the arms of said members are in contact.

55 7. A device of the class described comprising a base member insertable under the mattress of a bed, said base member consisting of a single length of wire of U-shaped formation, the end portion being straight and bent upwardly at right angles to the plane of the base and terminating in stops, a substantially U-shaped bed clothes supporting member arranged normally to rest on the top of a mattress and having loops encircling the uprights of said base member and said stops on said upwardly projecting portions of the base member serving to support the clothes support member in clothes supporting position.

60 8. A device for elevating bed clothes above a mattress including two members each fashioned from a single piece of wire rod material, one a base member having a bight with uprights rising from the bight, the other a clothes supporting member of substantially U-shape having a crosswise central portion and two arms terminating in loops encircling said uprights and which loops slideably and swingably travel on the base uprights, and stops on said uprights cooperating with said loops when said supporting member is raised for maintaining said supporting member in adjusted angular position on said base member.

65 9. A device of the class described including two relatively movable members, one of said members being L-shaped in side eleva-

tion with a horizontal portion thereof substantially U-shaped in plan, the upright ends of the L-shaped member being disconnected and each having a stop thereon, the other of said members being substantially U-shaped with loops in the ends of the arms thereof engaging the uprights of the first member, the plane of the loop of the second member being substantially perpendicular to the plane of the arms of the second member, the stops on the uprights of said first member being in the path of the arms of the second member when swung in one direction, said stops and said loops cooperating to maintain said two members in adjusted angular relation when said second member is swung against said stops.

In testimony whereof I have hereunto subscribed my name at Chicago, Cook County, Illinois.
